(57) **CLAIM**

The ornamental design for a portable power source as shown and described.

DESCRIPTION

FIG. 1 is a top front perspective view of a portable power source according to my new design;

FIG. 2 is a bottom front perspective view thereof;

FIG. 3 is a front side view thereof;

FIG. 4 is a rear side view thereof;

FIG. 5 is a right side view thereof;

FIG. 6 is a bottom view thereof; and,

FIG. 7 is a top view thereof.

The broken lines shown in the drawings illustrate portions of the portable power source that form no part of the claimed design.
